[57] CLAIM

The ornamental design for a combination golf putter and golf ball display stand and putt practice device, as shown.

DESCRIPTION

FIG. 1 is a rear perspective view of the combination golf putter and golf ball display stand and putt practice device;

FIG. 2 is a rear elevational view of the combination golf putter and golf ball display stand and putt practice device;

FIG. 3 is a front elevational view of the combination golf putter and golf ball display stand and putt practice device;

FIG. 4 is a side elevational view of the combination golf putter and golf ball display stand and putt practice device;

FIG. 5 is a bottom view of the combination golf putter and golf ball display stand and putt practice device;

FIG. 6 is a top plan view of the combination golf putter and golf ball display stand and putt practice device; and,

FIG. 7 is a side elevational view from the side opposite to FIG. 4 of the combination golf putter and golf ball display stand and putt practice device.

The broken line showing of a putter and golf ball on FIG. 1 is for illustrative purposes only and forms no part of the claimed design.
